MIRROR CONTAINING DRAWER FOR
CHESTS AND THE LIKE

Samuel L. Pollock, San Francisco, Calif.

Application August 5, 1933, Serial No. 683,842

4 Claims. (Cl. 45—97)

This invention relates to an article of furniture. More particularly the invention relates to the provision of a folding mirror within a drawer which is adapted to be fitted in a chest of drawers, a dresser or the like.

One of the principal objects of the invention is the provision of a folding mirror within a drawer as a means of economizing on space.

Another object of the invention is the provision of a folding mirror within a drawer which will be automatic in substantially all respects and be provided with a simple means for adjusting the angle of the mirror.

In this age, economy of space is constantly sought in places of residence by combining various articles of furniture and it was with this thought in mind that the present invention was devised. One of the objects of the invention is the provision of a simple, inexpensive and yet efficient attachment for the interior of a drawer constituting an equivalent for the well known dressing table.

It is known that a dressing table comprises a mirror and drawer space for cosmetics and the like and that this is usually a full sized article of furniture in and of itself. Thus in small bed-rooms and apartments it has been found impossible to have the ordinary conveniences afforded by both a dressing table and chest of drawers or a bureau due to limitations of space, and it was my idea that the necessary elements of the usual dressing table, particularly, the mirror, could be enclosed within a drawer fitted to a chest or bureau and concealed from sight when not in use, while at the same time saving the greatest portion of the drawer space for cosmetics and devices employed in the care of the person.

It is to be understood, of course, that the invention would function equally as well if applied to a drawer set in a recess in the wall of a bed-room or bathroom, where a chest or bureau is neither desirable or available.

Other objects of the invention will become apparent as the specification proceeds and the novelty of the invention will be particularly pointed out in the appended claims.

In the drawing, in which a preferred form of the invention is illustrated,

Fig. 1 illustrates the invention applied to the drawer of a chest of drawers,

Fig. 2 is a sectional view of the drawer containing the mirror and showing the latter in open position,

Fig. 3 is a similar section showing the mirror in a nearly closed position,

Fig. 4 illustrates the detail of the springs em-

ployed in adjusting the pitch of the mirror when in open position,

Fig. 5 illustrates the block used in conjunction with the spring just mentioned for the specified purpose, and

Fig. 6 is a detailed view of the connecting means for the mirror and slide blocks.

The numeral 1 designates a drawer of known construction set in a chest 2 and slidably mounted on the slides 3.

The mirror 4 has a frame 5 and is pivotally connected to the slide blocks 6 set in the interiorly disposed grooves 7 of the drawer 1 by means of the pins 8.

Rods 9 anchored in the side walls at the forward part of the drawer 1 and connected to the edges of the mirror frame 5 at a point slightly below the middle thereof, support the mirror when the latter is in an upright position and cause the pivotal connection of the mirror frame 5 and the blocks 6 to move rearwardly when the mirror is being folded.

Angle pieces 10 are set in the lowermost edges of the mirror frame, at the point where the same is connected to the blocks 6, with the free ends 11 projecting forwardly. Springs 12, anchored in the front wall of the drawer are connected to the ends 11 of the angle pieces 10 and supply the tension which is necessary to automatically raise the mirror when the drawer is pulled out of the chest 2.

The pitch of the mirror is rendered adjustable by means of the blocks 13 disposed in the grooves 7, in front of the slide blocks 6, and held at a fixed point therein by the springs 14. The springs 14 are anchored in the side walls of the drawer 1 by the inwardly bent pins or projections 15. A series of holes 17 are provided in the blocks 13 to receive the inwardly bent pins or projections 15 of the springs 14. The placement of the pins 15 in the holes 17 determines the pitch of the mirror.

It will be noted that in addition to serving as a means of adjusting the pitch of the mirror, the blocks 13 and springs 14 act as buffers for the blocks 6 as the mirror is pulled into the upright position shown in Figure 2, the shock being taken up by the springs 14.

Lamps 18 are bracketed onto the mirror frame 5, as shown in Figure 1, to illuminate the surface thereof, taking the place of those usually found attached to dressing tables adjacent to the mirror.

The operation of my device is as follows: As the drawer 1 is pulled out of the chest 2, the ten-

sion of the springs 12 on the bottom of the mirror frame 5, through the angle pieces 11, causes the blocks 6 to slide forwardly in the grooves 7. At the same time the rods 9 cause the mirror to be tilted backwardly toward the position shown in Figure 2. The blocks 13, having been set at a predetermined point in the grooves 7 by means of the springs 14, restrict the forward movement of the blocks 6 and thus set the pitch of the mirror.

10 It is to be understood that my invention is susceptible to many modifications and changes and I therefore do not wish to be limited by the specific form shown and described, but only to the extent of the appended claims.

15 Having thus described my invention, what I claim is:

1. A mirror containing drawer comprising grooves in the side walls of the drawer, slide blocks in said grooves, a mirror pivotally mounted on said slide blocks and normally housed in a horizontal position, links connected to the mirror on an axis located on one side of the axis of said slide blocks, a tensioning member connected to the mirror on the opposite side of said axis of said slide blocks, said links restricting forward movement of their connecting axis when the tensioning member draws the slide blocks forwardly.
2. A mirror containing drawer comprising grooves in the side walls of the drawer, slide blocks in said grooves, a mirror pivotally mounted on said slide blocks and normally housed in a horizontal position, links connected to the mirror on an axis located on one side of the axis of said slide blocks, tensioning members connected to the mirror on the opposite side of said axis

of said slide blocks, said links restricting forward movement of their connecting axis when the tensioning member draws the slide blocks forwardly, and means disposed in said grooves to determine the pitch of the mirror when the latter is in raised position.

3. A mirror containing drawer comprising grooves in the side walls of the drawer, slide blocks in said grooves, a mirror pivotally mounted on said slide blocks and normally housed in a horizontal position, links connected to the mirror on an axis located on one side of the axis of said slide blocks, tensioning members connected to the mirror on the opposite side of said axis of said slide blocks, said links restricting forward movement of their connecting axis when the tensioning member draws the slide blocks forwardly, and adjustable shock absorbing means disposed in said grooves to determine the pitch of the mirror when the latter is in raised position.

4. A mirror containing drawer comprising grooves in the side walls of the drawer, slide blocks in said grooves, a mirror pivotally mounted on said slide blocks and normally housed in a horizontal position, links connected to the mirror on an axis located on one side of the axis of said slide blocks, tensioning members connected to the mirror on the opposite side of said axis of said slide blocks, said links restricting forward movement of their connecting axis when the tensioning member draws the slide blocks forwardly, buffers disposed in said grooves in front of said slide blocks and means for adjusting the position of said buffers.

SAMUEL L. POLLOCK.
